[57] CLAIM

The ornamental design for a sign holder, as shown and described.

DESCRIPTION

FIG. 1 is a perspective view showing the sign holder of my new design;
FIG. 2 is a side elevational view thereof, with the opposite side being a mirror image, and with the center broken away for convenience of illustration only;
FIG. 3 is a top plan view thereof;
FIG. 4 is a bottom plan view thereof;
FIG. 5 is an end elevational view thereof, the opposite side being a mirror image thereof;
FIG. 6 is an enlarged sectional view taken along the line 6—6 of FIG. 2;
FIG. 7 is a perspective view of a second embodiment thereof;
FIG. 8 is a side elevational view thereof, with the opposite side being a mirror image, and with the center broken away for convenience of illustration only;
FIG. 9 is a top plan view of FIG. 7;
FIG. 10 is a bottom plan view of FIG. 7;
FIG. 11 is an end view of the left end of FIG. 7;
FIG. 12 is an end view of the right end of FIG. 7;
FIG. 13 is an enlarged sectional view taken along the line 13—13 of FIG. 8;
FIG. 14 is a perspective view of a third embodiment thereof;
FIG. 15 is a side elevational view thereof, with the opposite side being a mirror image, and with the center broken away for convenience of illustration only;
FIG. 16 is a top plan view of FIG. 14;
FIG. 17 is a bottom plan view of FIG. 14;
FIG. 18 is an end elevational view of the left end of FIG. 14;
FIG. 19 is an end elevational view of the right end of FIG. 14;
FIG. 20 is an enlarged sectional view taken along the line 20—20 of FIG. 15; and,
FIG. 21 is an enlarged sectional view taken along the line 21—21 of FIG. 15.
